Sam Stevens.

Attorney

UNITED STATES PATENT OFFICE

PETER SWANSON, OF ELY, MINNESOTA

SWITCH-STAND LOCK

Application filed January 6, 1930. Serial No. 418,768.

This invention relates to railroad switches and has special reference to that type of switch stand in which the hand operating lever must be first moved vertically in order to unlock the switch by movement of the vertically reciprocable head thereof, and which head is rotated with the switch staff when the switch is being thrown, and refers particularly to a novel form of lock for said lever, such lock resembling materially the type illustrated in my copending application Ser. 332,646.

The principal object of my present invention is to provide a lock of this type as completely housed as possible whereby to augment its efficiency and resistance to tampering.

Another object is to provide such a lock adaptable to a switch handle having either a long or a short switch stand lug.

A further object is to provide novel means for convenience in assembling the respective parts of the lock.

Still other objects and advantages of the novel structure will appear in the following description thereof.

Referring now to the accompanying drawing, forming part of this application, and wherein like reference characters indicate like parts:

Figure 1 is a side elevation of a fragmental portion of the upper end of a switch stand and operating lever showing my improved form of lock attached thereto, and partly in section and partly in elevation;

Figure 2 is a section on the line 2—2, Fig. 1, showing parts in elevation;

Figure 3 is an outer elevation of the lock viewed longitudinally of the handle; and

Figure 4 is an enlarged perspective diagram of the anti-tampering spring.

1 represents the vertically adjustable head of a common railroad switch stand of the type set forth, having fixed thereto the short lock engaging lug 2, common to such stands. This lug normally extends through either the lower bifurcated portion of the operating handle 3 when the latter is in closed position as shown in Figure 1 or through a

hole 4 provided therefor adjacent the bifurcated portion.

The handle 3 is bifurcated at its upper end as at 5 and pivotally mounted as at 6 upon the staff 7 of the switch stand and is connected as by the links 8 to the sides of the head 1 as at 9 so that when it becomes desired to throw the switch the handle is raised in order to raise the head from non-rotatable engagement with the stationary switch stand not shown so that the lever, staff and head may be rotated as desired, thus throwing the switch.

The lock housing 10 is rectangular in form and designed to stand in upright position adjacent the hole or slot 4 on the handle through which the lug 2 reciprocates, and the lower end of this housing is made to fit the contour of the handle and be either securely bolted, welded thereto, or formed integral therewith, as desired; though it is one object of my present invention to provide such a lock with a supporting extension therefor adaptable to different types of handles and stands.

The lock housing comprises also the secondary cover like portion 11 which is designed to fit down over the principal portion 10 prior of course to the installation of the rotatable locking bolt shaft 12 which latter is novel in respect to the manner of installation of same, which is as follows: The shaft is of the type described in my former applications having a portion of one side thereof cut away as at 13 whereby to permit of a locking dog illustrated at 32 becoming engaged behind same to hold it in non-rotatable position, which will be subsequently described. The shaft 12 is provided with the operating finger or handle portion 15 whereby to operate same manually and externally of the lock housing, and when in position within the lock extends horizontally through one outer wall of the housing and also through the auxiliary partition 16 therewithin, and from which point the shaft is tapered as at 17 transverse the space between the auxiliary wall 16 and the inner or adjacent wall of the housing 10. This tapered portion is for installation of the hub 18 of

the locking bolt 19 which is slightly arcuate in shape and extends downwardly with the holding extremity thereof at right angles to the body portion, and which extremity is designed to engage the hole 20 in the switch lug 2 when the switch is locked.

The innermost extremity 21 of the locking bolt shaft is still smaller in diameter than the smaller end of the tapered portion 17 forming an annular shoulder thereabouts. The registering holes within the inner wall of the housing proper and the cover member 11 are of a diameter slightly larger than the inner smaller end of the tapered portion 17 and into which is fitted a sleeve or bushing 22 to act as a bearing for the innermost end of the shaft 12; then, externally of the cover member 11, and onto the extreme end of the shaft 12, is fitted the locking ring or nut 23 as by the pin 24, or it may be threaded thereupon if preferred.

It is to be understood that the tapered portion 17 may be circular in cross section and the hub 18 of the locking dog splined thereupon or the tapered portion may be square and the hub similarly shaped to fit thereupon, but in either event the advantages of the novel features of the assembly are that the shaft 12 has three distinct rotatable bearings and characteristics in that for example, if, after being assembled for some time it becomes desirable to disassemble same, the process includes, of course, the removal of the nut 23 when the bushing 22 may be taken out leaving a space about the reduced portion 21 of the shaft through which a swage or hollow drift pin may be used in impinging the annular shoulder about the inner end of the reduced portion 21 and the shaft thus readily driven endways out of its engagement with the hub 18 of the locking bolt and removed from the lock housing.

It will further be noted that the shape and positioning of the housing is such that in the event of being employed upon a switch stand having a long horn or lug as indicated at 25 instead of the short horn 2 it will accommodate same therewithin; the long lug passing freely upwardly in the compartment 26 of the lock housing, it being offset from alignment with the shaft 12.

The keyhole for the lock is indicated at 27 having the key pin 28 therein, and the slot for the key wing is preferably formed angularly as at 29 so that keys for different railroad systems may have characteristics in the shape of the wings, as one convenience. The key pin 28 is fixed in the intermediate wall 30 as is a similar pin 31 just inwardly and above the key pin to act as a pivotal support for the locking dog 32. This locking dog 32 is provided with the L-shaped portion 33 which is partly cutaway on the line 34, the lower remaining portion being designed to drop when occasion permits into

the cutout notch 13 of the bolt shaft 12 to hold same as previously described, and by the way this gravity dog arrangement is in many respects similar to that shown in various of my copending applications. The opposite arcuate end 35 is designed to cover the lower portion of the key hole 27 when the locking dog is in its raised position as indicated in dotted lines Figure 1, while, when in its locked position, as for example when the locking dog 19 is in engagement with the lug 2, is free from acting as a closure to the key hole.

A further novel characteristic of this locking dog is that in addition to its being normally a gravity controlled lock, I have installed a spiral spring 36 about the pin 31 adjacent one side of the dog, one end of which is normally free for impinging engagement with the inside of the top of the lock cover 11 when applied to the lock, and the opposite end disposed longitudinally of the main body portion of the dog 32 where it is turned at right angles as at 37, such turned portion extending over the back of the dog tending to further hold the same in locked position, there, of course, being sufficient of the back side of the dog cut away to accommodate the installation and free action of the spring. This spring is provided against otherwise possible tampering with the lock and opening same by insertion of a crooked wire or other piece of material through the key hole adjacent the pin and raising the dog from its locked engagement with the bolt shaft, and the spring is of sufficient tension to overcome any power possible of exertion by such an unauthorized element. That is to say, it is intended to make this spring sufficiently strong so that any tampering tool would be bent or otherwise injured before the effect of the spring could be overcome and movement of the dog occur, it being understood that the wing portion of the hole is guarded by the dog 35.

At 38 is illustrated a second gravity locking dog suspended in pendulum like form on the pivot 39, directly above the lower free end of the locking dog 19, and in alignment with the opening in the lock into which the lug 2 of the switch stand extends, and in fact is provided as an automatic closure for said opening as well as a stop against which the free end of the locking bolt 19 impinges in the manual act of holding the bolt shaft 12 in its unlocked rotative position. That is to say when the shaft 12 is rotated manually as by the crank arm 15 for releasing the bolt 19 from engagement with the switch lug 2 the pendulum dog 38 will by gravity follow the extreme end of the lug 2 as it leaves the lock and thus present itself in front of the free end of the locking bolt 19 so that the latter will be thus held in its outermost or released position. In this manner the lock

is held ready for subsequent engagement with the lug 2, and as the lug again enters the lock it will push the pendulum dog from engagement with the locking bolt 19 and the latter will automatically drop within the hole 20 to locked position.

Here it must be explained that when the lock is used upon a switch stand having a long arcuately shaped prong as indicated at 25 and previously described, there is no occasion for the pendulum dog 38, which in such event is removed from the lock and entirely dispensed with, it being understood that the horn 25 is sufficiently long to always remain in contact with the locking bolt 19.

I have illustrated the housing as being of a convenient and neat shape, but it is evident that this may be varied without departing from the spirit of the invention which resides principally in as nearly as possible completely housing the lock mechanism.

Having thus described my invention, what I claim and desire to secure by Letters Patent, is:

1. The combination with a switch lock of the type described including a gravity bolt operable upon a rotatable shaft having manual operating means associated therewith, of a separable telescopic housing for completely inclosing the locking bolt, said housing being held in assembled relation by said shaft.

2. A switch stand lock of the type described comprising a telescopically separable housing, and a rotatable shaft within said housing carrying a manually and gravity controlled locking bolt, said shaft holding the housing in assembled relation.

3. A switch stand lock of the character described comprising a separable housing carried by the lever of the switch stand, a manually rotatable shaft within said housing carrying a gravity operated locking bolt for engagement with the lug of the switch stand, and means whereby said lock may accommodate either a short or long switch stand lug.

4. A switch stand lock of the type described having a rotatable shaft therein, a locking bolt carried by said shaft, a locking dog for intermittent engagement with the shaft, said lock having a key hole therein for insertion of a key to operate the dog, and means for holding the bolt in unlocked position when the handle is raised.

5. A switch stand lock comprising a telescopically separable housing, a manually rotatable shaft within said housing, a locking bolt removably mounted on said shaft, a locking dog for normally holding the shaft against rotation, and means for holding the bolt in unlocked position when the handle is raised.

6. A switch stand lock comprising a telescopically separable housing, a rotatable shaft within said housing having a bolt at one end for locking engagement with a hole

in the switch stand lug and at the other end a manually operable portion, said shaft holding the housing in assembled relation.

7. A switch stand lock comprising a housing of two telescopic halves, a rotatable shaft mountable transverse said halves when united, a locking bolt carried upon said shaft within the housing, and means externally of the housing for manually operating the bolt.

8. A switch stand lock housing characterized by being formed of two telescopic halves, the inner one having a hollow supporting bracket for the reception of a lug to be locked, and the outer half held in position by a shaft having a locking bolt thereupon.

9. The combination with the structure set forth in claim 4, of a spring associated with said locking dog to overcome the stress of a tampering tool insertable through the key hole.

In testimony whereof I affix my signature.

PETER SWANSON.
